US00D979284S

(12) **United States Design Patent** (10) Patent No.: **US D979,284 S**
(45) Date of Patent: **** Feb. 28, 2023**

(54) **FLUID DISPENSER COVERING**

(71) Applicant: **WELLA INTERNATIONAL OPERATIONS SWITZERLAND SÀRL**, Petit-Lancy (CH)

(72) Inventors: **Ann-Marie Gass**, Darmstadt (DE); **Hauke Schormair**, Griesheim (DE); **Massimo Morini**, Bad Soden (DE)

(73) Assignee: **WELLA INTERNATIONAL OPERATIONS SWITZERLAND SÀRL**, Petit-Lancy (CH)

(**) Term: **15 Years**

(21) Appl. No.: **29/765,515**

(22) Filed: **Jan. 8, 2021**

(51) LOC (14) Cl. **23-08**

(52) U.S. Cl. **USPC D6/545**

(58) **Field of Classification Search**

USPC D6/524, 542-545, 518, 519, 522;
D7/306, 312, 313, 321, 322, 391, 397,
D7/398, 307, 309, 600.1, 601, 619.1;
D23/208, 234, 286; D24/128, 234;
D28/38, 54.1; D20/1; D8/71; D9/455
CPC A47G 23/0258; B05B 11/00412; B05B
11/3047; A47K 5/1211

(57) **CLAIM**

The ornamental design for a fluid dispenser covering, as shown and described.

DESCRIPTION

FIG. 1 is a front-right perspective view of a fluid dispenser covering showing our new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The shade lines show surface contour and not surface ornamentation.
